United States Patent Office.

NICHOLAS S. VEDDER, OF TROY, NEW YORK, ASSIGNOR TO EDWARD J. HICKS AND GURDON G. WOLFE, OF SAME PLACE.

Design No. 2,988, dated March 31, 1868.

DESIGN FOR THE PLATES OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Plates of a Stove, of which the following is a full and exact description, reference being had to the accompanying photographs, in which—

Figure 1 represents the bottom plate,

Figure 2 the top plate and movable cover,

Figure 3 the door-frame and door, and

Figure 4 one of the legs of a stove having my said design.

My new design for the bottom plate, A, consists essentially of the series of ornaments *b* and *c*, shaped and arranged along the border of that plate, as shown in fig. 1. The design for the top plate D consists of three series of ornaments, *e f g*, shaped and arranged along the oval border of the plate, as shown in fig. 2. The design for the movable cover H consists of a series of border-ornaments, *i*, and internal radiations *j*, and scroll-work ornamentations *k*, all shaped and arranged as shown in fig. 2. The design for the door-frame L consists of the series of bracket-like ornaments *m*, and top and bottom scroll-work *n* and *o*, all shaped and arranged as shown in fig. 3. The design for the door P consists of the compound centre ornament *q*, ornamental moulding *r*, and border-ornaments *s*, all shaped and arranged together as shown in fig. 3. And the design for the leg T consists essentially of the upper central ornament *u*, and the ornamental sides *v v*, all shaped and arranged as shown in fig. 4.

What I claim as my invention or production, and desire to secure by Letters Patent, is—

The design for the plates or castings A, D, H, L, P, and T, of a stove, herein set forth and shown.

In testimony whereof, I hereunto set my hand, this 14th day of February, 1868.

NICHOLAS S. VEDDER.
